UNITED STATES PATENT OFFICE.

FRANCIS M. TAYLOR, OF PARKERSBURG, WEST VIRGINIA.

DESIGN FOR AN ADVERTISING MOTOR-CAR.

49,165.

Specification for Design.

Patented June 6, 1916.

Application filed March 22, 1916. Serial No. 85,999. Term of patent 3½ years.

To all whom it may concern:

Be it known that I, FRANCIS M. TAYLOR, a citizen of the United States, residing at Parkersburg, in the county of Wood and State of West Virginia, have invented a new, original, and ornamental Design for Advertising Motor-Cars, of which the following is a specification, reference being had to the accompanying drawing, in which—

Figure 1 is a side elevation of a motor car

embodying my new design; Fig. 2 is a top plan of the same; and Fig. 3 is a rear end elevation of the same.

I claim:

The ornamental design for an advertising motor car, as shown.

FRANCIS M. TAYLOR.

Witnesses:

H. E. DUNLAP,
W. F. KEEFER.
